DESIGN FOR A DOUGHNUT FORMING DEVICE

David F. Jones, Richmond, Calif., assignor to
Hom-Ade, Inc., Oakland, Calif., a corporation
of California

Application January 11, 1947, Serial No. 136,102

Term of patent 14 years

(Cl. D44—29)

To all whom it may concern:

Be it known that I, David F. Jones, a citizen of the United States and a resident of Richmond, county of Contra Costa, and State of California, have invented a new, original, and ornamental Design for a Doughnut Forming Device, of which the following is a specification, reference being had to the accompanying drawing, forming part thereof.

Figure 1 is a posterior perspective view of a doughnut forming device showing my new design.

Figure 2 is a perspective view of the device showing the reverse side thereof.

Figure 3 is a top plan view of the device.

I claim:

The ornamental design for a doughnut forming device, substantially as shown.

DAVID F. JONES.
